UNITED STATES PATENT OFFICE

DANIEL WOODHEAD, OF EVANSTON, ILLINOIS

LAMP AND GUARD HANDLE

Application filed October 9, 1929. Serial No. 398,345.

This invention relates in general to lamp and guard handles, and particularly to a lamp and guard handle, which is made of rubber or other like material.

5 The object of the invention is to provide a yieldable rubber guard handle which is provided with means whereby an electric socket member having an extension cooperating with an operating switch may be inserted 10 within the guard handle to permit operation of the switch without removing the socket member from the handle.

Another object is to provide a guard handle, which has an inner annular flange which 15 is engageable with a socket member, which has a longitudinal slot provided in the inside thereof which communicates with an opening through the guard handle to permit a socket member, having a switch attaching portion 20 to be readily inserted in the guard handle with the attaching portion and the operating switch extending through the hole.

Other objects and advantages will appear 25 throughout the progress of the following specification:

The invention comprises in general a lamp and guard handle which is provided with an annular flange and a reduced rear portion engageable with an electric light socket for 30 maintaining the socket in proper position in the guard handle. The handle is sufficiently large at one end and spaced from the socket to provide an air cushion between the socket and the exterior of the guard handle. A 35 longitudinal groove is provided in the guard handle and communicates with an opening therein, whereby an electric socket having a part which cooperates with an operating switch can be readily and quickly inserted 40 in the guard handle with the part or extension projecting through the hole in the guard handle. The switch or actuating member is operatively connected to the socket, permitting 45 the actuating member to be operated from the outside of the handle.

The guard handle or grip portion of the guard member is made hollow to accommodate the electrical conductors leading to the socket members, and an enlarged recess is 50 provided in the guard handle at the end of

the socket member to permit the conductors to be knotted at this point. Strains or stresses occurring on the conductors will be transmitted directly to the guard handle, preventing any direct pull on the electrical 55 connections of the conductors.

The accompanying drawings illustrate a selected embodiment of the invention, and the views thereof are as follows:

Fig. 1 is a longitudinal sectional view of 60 the lamp and guard handle showing the socket member arranged therein;

Fig. 2 is a similar view showing the manner in which the socket member is inserted 65 in position.

Referring to the drawings, 5 designates a guard handle generally having a hollow handle or grip portion 6 and a bell-shaped portion 7 to receive an electric socket 8. An inner annular flange 9 is provided at the forward edge of the bell-shaped portion to engage the reduced portion 10 of the socket 8. The rear end of the bell-shaped portion is reduced in diameter at 11 to engage the enlarged body portion 12 of the socket member 70 75 80

85 The portion lying between the shoulder 13, formed by the reduced end 11, and the shoulder 14 formed by the annular flange 9, forms an annular space 15, which provides an air cushion about the body of the socket member and absorbs any shock which may be caused by dropping the device or during ordinary use.

90 The annular flange 9 may be cut away at 16 to provide a longitudinal notch, and the reduced end 11 of the guard handle may also be slotted at 17, as clearly shown in the drawings. A hole 18 is provided through the body of the handle and communicates with the notch or slot 17. The location and construction of these notches and slots communicating with the hole 18 permits a projection on the socket member 8 to extend through the body of the handle and project through the outside of the handle. 95

100 In the present embodiment shown, the socket member has an annular hub or projecting member 19 provided on the enlarged portion 12 thereof through which an operating chain 20, Fig. 1, extends. An operating

member 21 is operatively connected to the chain 20 by means of a small screw 22. The present switch shown is capable of being operated by merely pushing the operating member 21 from any side. By pushing the member 21, the lower edge of the operating member 21, will engage the hub or projection 19 and cause a leverage for pulling the chain. The particular switch shown in the present case is merely for the purpose of illustration, and it is to be understood that other types of switches may be used.

The notch 16 permits the socket member 8 to be inserted in a tilting position, as shown in Fig. 2, to permit the hub or projection on the socket to be inserted in the bell-shaped portion of the lamp guard handle. The socket is then tilted until its longitudinal axial center line coincides with the axial center line of the guard handle. The socket member is then pushed inwardly with the hub or projection engaging the notch or slot 17 to permit free axial sliding movement of the socket member. The socket is then forced inwardly until the hub 19 extends through the hole 18 when the operating member 21 is fastened in position. As previously mentioned it is to be understood that instead of having the specific operating mechanism shown, other types of switch mechanisms may be employed, the invention providing means, whereby a socket member having a switch may be inserted inside of the guard handle with the switch extending through the guard handle to permit operation thereof. The guard handle is made of flexible rubber and is resilient and comparatively soft, so that it may bend and stretch within reasonable limits, during the insertion of the socket member.

A lamp guard 23 is provided with the usual annular clamp 24, which sets in a groove 25 provided on the outside of the guard handle. Tightening of the clamp 24 causes the inner annular flange 9 to impinge the body of the socket member and prevent it from moving out of position.

The invention provides a lamp and guard handle, which is provided with an air cushion about the socket member to prevent any shock from being transmitted to the body of the socket member. The annular groove and the reduced portion of the bell-shaped member has sufficient contact with the socket member to normally hold it in position. The notches and grooves provided in the inside of the guard handle, and the hole through the guard handle permits a socket having a switch member to be readily inserted in position in the guard handle. The lamp guard 23, which is provided with a clamp 24 rests in the exterior annular groove 25, as clearly shown in Fig. 1.

Changes may be made in the form, construction and arrangement of the parts with-

out departing from the spirit of the invention, or sacrificing any of its advantages, and the right is hereby reserved to make all such changes, as fairly fall within the scope of the following claims.

The invention is hereby claimed as follows:

1. A guard handle made of flexible rubber having a grip portion and a bell-shaped end portion for receiving a socket member, said bell-shaped member having a reduced portion for engagement with the socket member, an interior annular flange in said bell-shaped portion and engageable with said socket member, a projecting member on said socket member, said reduced portion having a hole therein, the annular flange being notched and the reduced portion having a slot in its inner wall communicating with the hole, whereby the projecting member on the socket member may be readily inserted in said guard handle and extended through said hole.

2. A guard handle made of flexible rubber having a grip portion and a bell-shaped end portion for receiving a socket member, said bell-shaped end having a reduced portion for engagement with the socket member, an interior annular flange in said bell-shaped portion and engageable with said socket member for holding the socket member in place and forming an air cushion thereabout, a projecting member on said socket member, said reduced portion having a hole therein, the annular flange being notched, the reduced portion having a slot communicating with the hole, whereby the projecting member on the socket member may be readily inserted in said guard handle and projected through said hole, a lamp guard, and a clamping ring for said lamp guard and engaging an annular groove on the outside of said handle.

3. In a portable electric lamp, an electric switch socket having a projection thereon, a flexible rubber handle guard receiving said socket, an annular flange at the end of said guard and engaging the socket, said handle guard having a groove, said annular flange having a groove slining with the groove in the handle guard, said handle guard having an opening therein at the bottom of the groove whereby said socket may be inserted in the handle guard with the projection on the socket extending through the hole in the guard, said groove in the handle and annular flange accommodating the projection to permit the socket to be inserted in the handle.

4. A guard handle made of flexible rubber material and having a handle or grip portion and a bell-shaped end, an annular flange arranged in the bell-shaped end, a socket member insertable in the bell-shaped end and engageable with the annular flange whereby the socket member will be spaced from the walls of the bell-shaped end to provide an air cushion about a part of the socket

member to prevent shocks and jolts applied to the handle from being transmitted to the socket member, said handle having an opening therein and a groove communicating with the opening, said annular flange having a groove therein in alinement with the groove in the handle member, and a projection on the socket member and adapted to extend through the opening in the handle, the grooves in the handle member and the annular flange receiving the projection on the socket member when the socket is being inserted in position in the handle.

In witness whereof, I have hereunto subscribed my name.

DANIEL WOODHEAD.
